UNITED STATES PATENT OFFICE.

JOHN F. BRIGGS, OF GAYS MILLS, WISCONSIN, ASSIGNOR OF ONE-HALF TO SAMUEL C. MARTNER, OF PRAIRIE DU CHIEN, WISCONSIN.

CONVERTIBLE FOLDING GO-CART.

1,271,270.

Specification of Letters Patent.

Patented July 2, 1918.

Application filed February 26, 1916. Serial No. 80,578.

To all whom it may concern:

Be it known that I, JOHN F. BRIGGS, a citizen of the United States, and resident of Gays Mills, in the county of Crawford and State of Wisconsin, have invented new and useful Improvements in Convertible Folding Go-Carts, of which the following is a description, reference being had to the accompanying drawings, which are a part of this specification.

This invention has for its object to provide a child's go-cart capable of folding into a compact form so as to occupy small space for convenience in storing or on taking it aboard a street car or the like.

Another object of the invention is to provide such a go-cart capable of completely collapsing in one operation, that of moving the handle bar toward the front of the frame, hinged wheel supporting frames being automatically folded together beneath the frame in such operation.

Another object of the invention is to provide such a folding go-cart with a detachable portion including the seat and its back and the handle bars which are so combined together that they are capable of assuming various useful forms such as a high chair, a swing, or a two-wheel cart.

Another object of the invention is to provide for various adjustments of the parts in their different arrangements and for bracing and supporting the parts against accidental displacement in all of such arrangements.

Another object of the invention is to perfect details of construction of such a device.

With the above and other objects in view the invention consists in the convertible folding go-cart as herein claimed and all equivalents.

Referring to the accompanying drawings, in which like characters of reference indicate the same parts in the different views,

Figure 1 is a longitudinal sectional view of a convertible go-cart constructed in accordance with this invention, showing the device as it appears when opened up for use as a go-cart, an alternative position for the seat back and an alternative position for the boot being shown in dotted lines;

Fig. 2 is a side view thereof when folded or collapsed to its compact form;

Fig. 3 is a bottom view thereof;

Fig. 4 is a side view of the central por-

tion thereof showing the manner of disconnecting the detachable portion from the frame;

Fig. 5 is a sectional elevation of the detachable portion arranged as a high chair;

Fig. 6 is a similar view thereof when arranged as a swing;

Fig. 7 is a rear view of the device when so arranged;

Fig. 8 is a side view of the detachable portion when arranged to constitute a two-wheel cart when two of the wheels of the truck are attached thereto, but having the near wheel removed;

Fig. 9 is a detail view showing the detachable mounting for the wheels;

Fig. 10 is a similar view showing the arrangement of the locking pin;

Fig. 11 is a detail view of the sliding connection between the seat members and the handle bars; and

Fig. 12 is a detail view of the detachable connection between the handle bars and the links of the truck.

In these drawings 15 indicates a rectangular frame which is preferably of metal, as is true also of other parts unless otherwise indicated. Angle lugs 16 have rectangular wheel frames 17 pivotally connected thereto at each side of the frame. Axle pins 18 are secured in the lower corners of the wheel frames 17, and wheels 19 are removably mounted on them, as shown in detail in Figs. 9 and 10. Each wheel is rotatably mounted on a flanged sleeve 20 which carries a curved lever 21 with a pivoted locking pin 22 thereon entering an opening in the end of the axle pin 18, the removal of the pin from said opening permitting the wheel and its sleeve to be withdrawn for purposes which will be later explained.

Handle bars 23 are provided near their lower ends with outwardly projecting pivot pins 24 which are removably seated in open bearings formed by notched lugs 25 on the sides of frame 15, and retaining hooks 26 on said lugs engage the pins 24 when so seated to retain them in their pivotal connection with the frame. These handle bars are connected at their curved lower ends by a cross bar 27 and from a short distance above the pivot pins 24 to their upper ends are preferably formed semi-circular in cross section to produce a split tubular formation with similarly shaped supplemental

handle bar members 28 which are pivotally connected thereto at 29, the upper ends of the handle bar members 23 and 28 being connected by half round cross pieces 30, preferably of wood, which together form the round handle portion of the handle bars. Lugs 31 projecting from the concave surface of the supplemental handle bar members 28 are adapted to pass through openings in the handle bar members 23, and have tie rods 32 pivotally connected to them to also pass through such openings, but which are provided with stop pins or other enlargements 33 incapable of passing through the openings and thus limiting the degree of swinging movement of the supplemental handle bar member with respect to the main handle bar. When the handle bar members are together the tie rods 32 swing against the handle bar members 23 to prevent the supplemental handle bar members from swinging away from the handle bar proper.

Levers 34 are fulcrumed to the sides of the frame 15 and have links 35 pivoted to their upper ends, the rear ends of said links being provided with headed studs 36 adapted to be releasably engaged with the handle bars by fitting in registering notches 37 of the members 23 and 28. Swinging movements of the handle bars on their pivot pins 24 will thus be imparted to the levers 34 through the link connections 35. The lower ends of the two levers 34 are connected together by a cross piece 38, and S-shaped cam strips 39 are connected at their ends to the levers 34 and the crosspiece 38 respectively, as best seen in Fig. 3. The reversely bent cam portions thereof are spaced from the levers 34, as best seen in Fig. 1, and arc-shaped rods 40 rigidly connected to the tops and the front ends of the wheel frames 17, and lying in the plane thercof, pass between the lower ends of levers 34 and the cam strips 39. Thus the swinging movements of the levers 34 cause the wheel frame 17 to swing on the pivot lugs 16 of the main frame, the swinging of the handle bars toward the front ends of the main frame causing the cam strips 39 to press inwardly on the rods 40 to fold the wheel frames beneath the main frame, and the swinging of the handle bars in the opposite direction causing the levers 34 to bear outwardly on said rods 40 to swing the wheel frames to their vertical positions. In the fully extended position of the handle bars the parts are locked against accidental change in position by shouldered folding braces 41 connecting the levers 34 with frame 15. In this position of the parts the lower ends of the levers 34 of the U-shaped frame formed by the two levers 34 and their connecting crosspiece 38 by fitting between the rods 40 of the two wheel frames serve to prevent an inward movement of said

wheel frames, while the upper ends of the wheel frames by bearing against the outside of the main frame prevent a further outward movement thereof, and the wheel frames are thus held rigidly in their vertical positions. 70

To further rigidly brace the wheel frames in their upright positions a U-shaped member 42 has its ends pivotally mounted on the frame 15 and is connected by connecting rod 43 with the levers 34 so that as the device is opened up said member is swung downwardly between the rear ends of the wheel frames 17 to prevent them from swinging inwardly, though this blocking condition is removed by said member being swung upwardly when the device is being collapsed, movement being imparted thereto from the levers 34 by means of the connecting rods 43. 80

A pair of broad, flat members 44 and 45 preferably of wood, are hinged together and form the seat and back for the device in its various arrangements, the seat being formed by the part 44 in some instances and by the part 45 in others. In the arrangement being described, in which the device forms the folding go-cart, the part 44 constitutes the seat member and the part 45 the back member. Pivot pins 46 by which the members 44 and 45 are hinged together slidably fit in longitudinal slots of the handle bars 23 just above the pivot pins 24 so that the seat and back are capable of a limited vertical movement, and leaf springs 47 on the bottom of the seat member 44 bear at their front ends on a cross brace 48 which extends across the frame 15 to give a spring cushioning action to the seat. Such spring cushioning action is further produced by leaf springs 49 secured to the cross bar 27 and bearing on the bottom of the seat member, or rather against a tray 50 which is pivotally connected to the member 44 by bent arms 51, and which tray in this arrangement of the device is folded against the bottom of the seat member 44. An arm rest is formed on each side of the seat by a straight rod 52 and a curved rod 53, the two being pivotally connected together, and the former being pivotally connected to the member 44, while the latter is pivotally connected to the handle bar 23, preferably at the pivotal connection 29 for the supplemental handle bar member, as shown. 100

The back member 45 has an extension member 54, preferably of wood, slidably mounted on the back thereof by means of hooks 55 on the edge of each member engaging the edge of the other; and a U-shaped piece 56 with its ends pivotally connected to the member 45, preferably on the hooks 55 thereof, engages a hook 57 at the outer edge of the extension 54 to hold the latter in its extended position. A notched rib 58 on the 110

back of extension 54 is adapted to have its notch engaged with a central, angular offset or crank portion of a U-shaped bail wire 59 which is pivotally mounted at its ends in 5 brackets 60 projecting from the supplemental handle bar members 28, the relation of the parts being such that the bail 59 constitutes a brace for supporting the seat back 45 in its upright position. An arc-shaped 10 guard 61 is secured to the back of the extension 54 and is spaced from the rib 58 to confine the bail wire, but by disengaging the bail wire from the notch of the rib the seat back may be swung downwardly to the position 15 shown in dotted lines where the bail wire again supports it to allow the child to assume a reclining position.

A U-shaped boot frame 62 is pivotally mounted at its ends to the levers 34 a short 20 distance above the pivotal connections of the latter with the frame and extends forwardly approximately parallel with the frame to a point where it is connected by links 63 with the frame from which point it is preferably 25 inclined upwardly as shown, and a boot 64 of oil cloth or other suitable flexible material is attached to the front end of the boot frame 62 and is provided with detachable fasteners 65 adapted to engage with either a set of 30 complementary members at the front edge of the seat 44 or a similar set at the rear edge thereof, the first connection permitting the boot to hang, as shown in full lines in Fig. 1, and the latter connection causing it to be 35 stretched straight as shown by dotted lines. The latter position of the boot is more comfortable for the child when he is in a reclining position.

The construction and operation of the device when forming a folding go-cart will 40 now be understood, all parts being firmly held in their respective positions while the go-cart is in use to constitute a serviceable vehicle capable of necessary adjustments to 45 adapt it to a sitting position or a reclining position of the occupant, and the seat being cushioned by the springs 47 and 49 to make it comfortable. When it is desired to fold the go-cart to collapse it in the compact condition shown in Figs. 2 and 3, and thus enable it to be taken aboard a street car or the like, it is only necessary to break the joint of the folding braces 41 and swing the cross-piece 30 of the handle bar toward the front 55 end of the frame 15, thus causing the seat to fold against its back and swinging the levers 34 to remove the locking member 42 from between the wheel frames and folding the wheel frames beneath the main frame 60 while also folding the boot frame 62 into the main frame.

To remove the detachable portion of the device and convert it into a high chair the rods 32 are raised so as to permit them to 65 pass through the openings of the handle

bars 23, and the supplemental handle bar members 28 are swung away from the handle bar proper, thus liberating the headed pins 36 of links 35 from their confinement between the notches 37 and allowing said links 70 35 to be swung out of the way, as shown in Fig. 4. The hooks 26 are swung back as shown in this figure and the handle bars with the seat and back may then be lifted from the truck, and by standing it on the ends of 75 the handle bar sections which are spread apart as far as will be permitted by the tie rods 32 the device will be self supporting as shown in Fig. 5. It is now necessary to disengage the U-shaped piece 56 from the 80 hook 57 and allow it to swing downwardly to become a footrest, and then the extension 54 is pushed rearwardly so as to slide beneath the member 45 which is to constitute the seat, there being a notched arm 66 on the 85 member 45 alongside of and corresponding with the notched rib 58 so that it is only necessary to engage the bail wire 59 in their registering notches to lock the seat in its horizontal collapsed condition. The tray 90 50 is swung forwardly to rest upon the arm rests 52, and a hook 67 on the seat back 44 is engaged with the cross bar 27 to lock the seat back against swinging. The device now 95 constitutes a serviceable high chair, all parts being firmly held in place.

In order to convert the high chair into the swing shown in Figs. 6 and 7, it is only necessary to lift the seat so as to disengage the bail wire 59 from the notches of the rib 58 and the arm 66, and then draw out the extension 54 and lock it in its extended position by engaging the U-shaped piece 56 with the hook 57, as when the device was in the go-cart form. Then the hook 67 may be 100 disengaged from the crosspiece 27 and the tray 50 may be swung over the back member 44 and engaged with the crosspiece 27, the back 44 swinging forwardly to permit thereof, and then the handle bar members 105 23 and 28 are swung together and engaged by the tie rods 32 as originally, and the device is inverted and suspended by springs 110 68, or otherwise, which may be engaged with projections 69 provided for the purpose on the ends of the handle bar members 23. This changed position is not very different 115 from the position of the parts in the go-cart formation, as will be seen by comparing Fig. 6 with Fig. 1, the main difference being that the handle bars are swung forwardly and the tray is engaged directly with the cross bar 27 to constitute a brace for the seat, while the back 44 is connected to the handle bars by the bail wire 59 in the manner shown by dotted lines in Fig. 1. A shoulder may be formed on the tray to prevent the tray from slipping from the cross bar 27 when the device is in this position, such shoulder being shown as formed by a turn 120 125 130

button 70 on the bottom of the tray. In this position of the device it constitutes a serviceable swing or baby jumper, the seat and back being firmly held in place with relation to the suspending handle bars, and the arm rests 52 and 53 guarding the sides of the seat to prevent the child from falling therefrom.

To now convert the swing shown in Fig. 6 into the two-wheel cart shown in Fig. 8, the foot-rest 56 may be disengaged from the hook 57 and the extension 54 collapsed, and then by swinging the seat member 44 into the plane of the handle bars the arm 10 rests 52 and 53 may have their elbow joints bent downwardly instead of upwardly, and by reengaging the lug 70 with the cross bar 27 the parts will be in the position shown in Fig. 8, and it is only necessary to re- 15 move two of the wheels from the truck and lock them in position on the pins 24, and the two-wheel cart is completed. In this condition of the device it constitutes a serviceable two-wheel cart with parts firmly held 20 in place and the foot-rest in position for use.

It is obvious that the device may be changed from any operative condition to any other without the necessity for following the course herein outlined.

30 The device constitutes a convertible article of furniture whether it is associated with the truck or separate therefrom and the term "convertible article of furniture" as herein used is therefore intended to generically include the various forms which this device may assume as well as others of an analogous character.

What I claim as new and desire to secure by Letters Patent is:

40 1. A folding go-cart, comprising a main frame, handle bars pivotally mounted thereon, a seat and back pivotally connected together and mounted on the handle bars, levers fulcrumed on the main frame, links 45 connecting the levers with the handle bars, wheel frames pivotally mounted on the sides of the main frame, wheels thereon, arc-shaped rods on the wheel frames, and cam strips carried by the levers engaging the arc-shaped rods for folding the wheel frames beneath the main frame when the levers are 50 swung by a folding movement of the handle bars.

55 2. A folding go-cart, comprising a main frame, handle bars pivotally mounted thereon, levers fulcrumed on the main frame, links connecting the levers with the handle bars, wheel frames pivotally mounted on the sides of the main frame, wheels thereon, 60 cam strips mounted on the levers and spaced therefrom, and arc-shaped rods on the wheel frames confined between the cam strips and the levers.

3. A folding go-cart, comprising a main

frame, handle bars pivotally mounted thereon, levers fulcrumed on the main frame, links connecting the levers with the handle bars, wheel frames pivotally mounted on the sides of the main frame, wheels thereon, cam strips mounted on the levers and spaced 70 therefrom, arc-shaped rods on the wheel frames confined between the cam strips and the levers, a blocking frame pivotally mounted on the main frame and fitting between the wheel frames, and connecting 75 rods connecting the blocking frame with the levers.

4. A folding go-cart, comprising a main frame, handle bars pivotally mounted thereon, levers fulcrumed on the main frame, links connecting the levers with the handle bars, wheel frames pivotally mounted on the main frame, wheels thereon, folding connections between the levers and the wheel frames, a boot frame pivotally connected with the levers, links connecting the boot frame with the main frame, a folding seat and back mounted on the handle bars, and a flexible boot connected 80 between the boot frame and the seat.

5. A folding go-cart, comprising a main frame, handle bars pivotally mounted thereon, levers fulcrumed on the main frame, links connecting the levers with the handle bars, wheel frames pivotally 90 mounted on the main frame, wheels thereon, folding connections between the levers and the wheel frames, a boot frame pivotally connected with the levers, links connecting the boot frame with the main frame, a folding seat and adjustable back mounted on the handle bars, and a flexible boot connected 95 between the boot frame and the seat and having detachable connections with the seat in different positions thereon.

100 6. A folding go-cart, comprising a main frame, handle bars pivotally mounted thereon, levers fulcrumed on the frame, links connecting the levers with the handle bars, wheel frames pivotally mounted on the main frame, 110 wheels thereon, folding connections between the wheel frame and the levers, hinged seat and back members slidably mounted on the handle bars, a cross bar connecting the lower ends of the handle bars, a cross brace on the frame, and springs between the cross brace 115 and the seat and between the cross bar and the seat.

120 7. A folding go-cart, comprising a main frame, handle bars pivotally mounted thereon, levers fulcrumed on the main frame, links connecting the levers with the handle bars, wheel frames pivotally mounted on the main frame with their upper ends bearing against the main frame, 125 wheels on the wheel frames, cam strips on the lever spaced therefrom, arc-shaped strips on the wheel frames confined between

the levers and the cam strips, a blocking frame pivotally mounted on the main frame and fitting between the wheel frames, links connecting the blocking frame with the levers, folding braces between the levers and the main frame, a boot frame pivotally connected with the levers, links connecting the boot frame with the main frame, a hinged seat and back slidably mounted on the handle bars, a crosspiece on the main frame, a cross bar connecting the lower ends of the handle bars, springs between the cross brace and the seat and between the cross bar and the seat, an adjustable connection between the handle bars and the back, and a flexible boot between the boot frame and the seat.

8. A convertible, folding go-cart, comprising a truck consisting of a main frame, wheel frames pivotally mounted thereon, wheels on the wheel frames, levers fulcrumed on the main frame and having folding connections with the wheel frames, and links pivotally connected with the levers; and a detachable section comprising a double set of handle bars pivotally connected together and detachably and pivotally connected with the main frame and with the links respectively, and seat and back members carried by the handle bars, said seat and back members and handle bars constituting a high chair when detached from the truck and stood upon the spread ends of the handle bars as legs.

35 9. A convertible, folding go-cart, comprising a truck consisting of a main frame, wheel frames pivotally mounted thereon, wheels on the wheel frames, levers fulcrumed on the main frame and having folding connections with the wheel frames, and links pivotally connected with the levers and provided with headed studs on their ends; and a detachable section comprising a double set of handle bars pivotally connected together and detachably and pivotally connected with the main frame and detachably engaging the headed studs of the links between them, and seat and back members carried by the handle bars, said seat and back members and handle bars constituting a high chair when detached from the truck and stood upon the spread ends of the handle bars as legs.

10. A convertible article of furniture, comprising a pair of seat members hinged together to alternatively constitute a seat and its back, a pair of elongated members pivotally connected to the seat members, a supplemental elongated member pivotally connected with each of said elongated members, a bail having pivotal connection with the elongated members and engaging one of the seat members, and pairs of hinged rods connected to the sides of the other seat

member and to the elongated members to 65 form arm rests.

11. A convertible article of furniture, comprising a pair of seat members hinged together to alternatively constitute a seat and its back, a pair of elongated members pivotally connected to the seat members, a supplemental elongated member pivotally connected with each of said elongated members, a hinged link connection between each elongated member and its supplemental elongated member mounted on one of said members and passing through an opening in the other to hold them together and to limit their swinging movement with relation to each other, a bail having pivotal connection with the elongated members and engaging one of the seat members, pairs of hinged rods connected to the sides of the other seat member and to the elongated members to 70 form arm rests, and a stop on the elongated members for determining the position of the last mentioned seat member.

12. A convertible article of furniture, comprising a pair of seat members hinged together to alternatively constitute a seat and its back, a pair of elongated members pivotally connected to the seat members, a supplemental elongated member pivotally connected with each of said elongated members, an extension slidably mounted on one 85 of the seat members, a U-shaped piece pivotally mounted on said seat member and adapted to engage the extension for holding it in its extended position, hooks on the back of said seat member and the extension 90 respectively, a bail having pivotal connection with the elongated members and adapted to engage one or both of the hooks, pairs of hinged rods connected to the sides of the other seat member and to the elongated 95 members to form arm rests, and a stop on the elongated members for determining the position of the last mentioned member.

13. A convertible article of furniture, comprising a pair of seat members hinged together to alternatively constitute a seat and its back, a pair of elongated members pivotally connected to the seat members, a supplemental elongated member pivotally connected with each of said elongated members, an extension slidably mounted on one 110 of the seat members, a U-shaped piece pivotally mounted on said seat member and adapted to engage the extension for holding it in its extended position, hooks on the back of said seat member and the extension respectively, a bail having pivotal connection with the elongated members and adapted to engage one or both of the hooks, pairs of hinged rods connected to the sides of the other seat member and to the elongated 115 members to form arm rests, and a stop on the elongated members for determining the position of the last mentioned member.

14. A convertible article of furniture, comprising a pair of seat members hinged together to alternatively constitute a seat and its back, a pair of elongated members pivotally connected to the seat members, a supplemental elongated member pivotally connected with each of said elongated members, an extension slidably mounted on one 120 of the seat members, a U-shaped piece pivotally mounted on said seat member and adapted to engage the extension for holding it in its extended position, hooks on the back of said seat member and the extension respectively, a bail having pivotal connection with the elongated members and adapted to engage one or both of the hooks, pairs of hinged rods connected to the sides of the other seat member and to the elongated 125 members to form arm rests, and a stop on the elongated members for determining the position of the last mentioned member.

sition of the last mentioned seat member, and a tray pivotally connected to the last mentioned seat member and adapted to engage the stop.

14. A convertible article of furniture, comprising a pair of seat members hinged together to alternatively constitute a seat and its back, a pair of elongated members pivotally connected to the seat members, a supplemental elongated member pivotally connected with each of said elongated members, an extension slidably mounted on one of the seat members, a U-shaped piece pivotally mounted on said seat member and adapted to engage the extension for holding it in its extended position, hooks on the back of said seat member and the extension respectively, a bail having pivotal connec-

tion with the elongated members and adapted to engage one or both of the hooks, pairs of hinged rods connected to the sides of the other seat member and to the elongated members to form arm rests, a stop on the elongated members for determining the position of the last mentioned seat member, a tray pivotally connected to the last mentioned seat member and adapted to engage the stop, pins projecting from the sides of the elongated members, and wheels removably mounted on the pins.

In testimony whereof, I affix my signature, in presence of two witnesses.

JOHN F. BRIGGS.
